APPLIQUE TYPE PANEL FOR CABINET DOORS
OR THE LIKE

John R. Morgan, Wheeling, Ill., assignor to Amerock Corporation, Rockford, Ill., a corporation of Connecticut

Filed Dec. 19, 1966, Ser. No. 5,077

Term of patent 14 years

(Cl. D13—1)

FIG. 1 is a perspective view of an applique type panel for cabinet doors or the like embodying my new design, the broken line illustration of several associated panels being shown for illustrative purposes only.

FIG. 2 is a front view of the medallion.

FIG. 3 is an enlarged sectional view taken along the line 3—3 in FIG. 2.

FIG. 4 is an enlarged sectional view taken along the line 4—4 in FIG. 2.

I claim:

The ornamental design for an applique type panel for cabinet doors or the like, as shown and described.
